REMOTELY RELEASABLE SAFETY BELT BUCKLE
Benjamin F. Schmidt, 450 Fairview St.,
Sierra Madre, Calif.
Filed June 24, 1963, Ser. No. 289,984
14 Claims. (Cl. 24—75)

This invention relates to safety belts such as used by occupants of vehicle seats to prevent injury of the occupants in the event the vehicle is stopped suddenly to avoid a collision or is involved in a collision accident.

In safety belts presently available the buckle or locking means are located in front of the user and can be released or unlocked only by appropriate manipulation which in some cases may prove difficult. If the user of the belt is injured opening of the belt may prove difficult and in some cases impossible. This is particularly the case if the injured person falls or leans over the buckle or locking means, and this difficulty is greater if the injured person is of large stature. If the injured person is unconscious or is unable to open the belt, a person seeking to rescue the injured person must reach to the front of the injured person to get at the buckle or locking means. This will prove difficult and may result in failure to effect a timely release, especially if the vehicle is on fire or a quick treatment is required to avoid death of the injured person.

It is the primary object of this invention to provide an improved safety belt which when locked around the occupant of a vehicle seat, may be released and opened much more quickly and with less effort than heretofore possible with safety belts and without requiring that the occupant or a person seeking release of the occupant actually touch or directly handle the buckle or fastening means for locking the belt.

It is another object hereof to provide a safety belt such as described having novel coupling means for positively locking the belt in place and which is subject to being unlocked by a simple and easily effected manipulation of novel releasing means disposed at locations remote from the coupling means but readily accessible to the user or to a person seeking to open the belt to free the user.

A further object hereof is the provision of a safety belt which will achieve the above described and other objectives herein noted by having embodied in the coupling means for locking the belt in place, novel releasing means operable in response to manipulation of either of a pair of flexible releasing elements which extend from the locking means in opposite directions and outwardly of the belt so as to partially surround the person embraced by the belt. With this arrangement the flexible elements are extended around the front of the user on opposite sides of the coupling means as well as along opposite sides of the user so that any portion of either flexible element readily may be grasped and pulled to effect operation of the releasing means and the unlocking of the coupling elements to open the belt.

A further object of this invention is the provision of a belt such as described wherein the coupling means for locking the belt around the user is capable of a hinge action so as to conform comfortably to the curvature of the body of the user, the coupling means also readily lending itself to being protectively covered or coated so that corners or other portions of the coupling means will be protected from damaging, marring, or injuring objects or parts of the body or the clothing of the user coming into contact therewith.

Other objects and advantages of the invention will be hereinafter described or will become apparent to those skilled in the art, and the novel features of the invention will be defined in the appended claims.

Referring to the drawings:

FIG. 1 is a top plan view of a safety belt embodying the present invention as it would appear when in use around the body of an occupant of a vehicle;

5 FIG. 2 is a fragmentary perspective view of the belt shown in FIG. 1, on an enlarged scale showing the buckle elements locked together;

10 FIG. 3 is an enlarged fragmentary longitudinal sectional view of the belt showing the buckle elements locked together;

FIG. 3a is a fragmentary sectional view showing parts of the coupling member as when separated;

FIG. 4 is a sectional view taken on the line 4—4 of FIG. 3;

15 FIG. 5 is a sectional view taken on the line 5—5 of FIG. 3;

FIG. 6 is a fragmentary elevational view partly in section of a modified form of this invention;

20 FIG. 7 is a fragmentary sectional view taken on the line 7—7 of FIG. 6;

FIG. 7a is a fragmentary perspective view of a part of one of the coupling members shown in FIGS. 6 and 7;

FIG. 8 is a fragmentary sectional view of another modified form of this invention;

25 FIG. 9 is a longitudinal sectional view taken on the line 9—9 of FIG. 8;

FIG. 10 is a sectional view taken on the line 10—10 of FIG. 9;

30 FIG. 11 is a fragmentary sectional view of another modified form of this invention; and

FIG. 12 is a sectional view taken on the line 12—12 of FIG. 11.

An illustrative embodiment of this invention as shown in FIGS. 1—5 includes a safety belt A anchored as at B 35 to a vehicle body C and provided with a special form of fastening means generally designated D operable to lock the belt securely around the body of an occupant of a seat of the vehicle. The belt A may be of any suitable strong and flexible fabric or similar belt material which 40 will comfortably conform to the body of the occupant of the seat and securely hold the occupant from being thrown out of the vehicle or thrown forwardly and injured by striking portions of the vehicle in front of the seat, in the event the vehicle is stopped suddenly or becomes involved in a collision accident.

The belt A may be provided between its ends with suitable adjusting means E as shown in FIG. 1, whereby it may be adjusted to fit the particular user. When this adjusting means is embodied in the belt it is preferable 50 to anchor the belt by means of flexible straps F secured to the belt and the vehicle body as indicated in FIG. 1.

In accordance with this invention, the fastening means D includes a female coupling member 1 and a male coupling member 2 fastened to the ends of the belt A, and 55 adapted to be locked together, subject however, to being unlocked solely in response to manually operable flexible elements or lanyards 3 and 4. These lanyards extend loosely along the outer sides of the belt in opposite directions from the coupling members 1 and 2 to which they

60 are operatively connected and may be fastened at points adjacent the rear of the belt as at 5. With this arrangement portions of the lanyards 3 and 4 on opposite sides of the belt will have appropriate slack and form loop portions 5a subject to being grasped and pulled at points remote from the coupling members 1 and 2, to unlock the coupling members and open the belt. Accordingly, the user of the belt quickly may reach down on either side of the belt to grasp and pull on either lanyard for unlocking the coupling members. Moreover, if the user of 65 the belt is injured or unconscious, a person seeking to rescue the user readily may grasp either lanyard and thus open the belt to release the injured person from the belt.

70

The female coupling member 1 includes a housing 6 to which one end of the belt A is secured in any suitable manner and which is provided with a socket portion 7 for receiving the male coupling member 2. In a pair of opposed members 8 fixed within the housing 6 and which define therebetween the socket portion 7, are depressions 9 for receiving a pair of locking balls 10 carried by the male member 2 for locking the coupling members together.

The male coupling member 2 includes a tubular member 11 carried by a cross member 12 to which the belt is secured in any suitable manner. The tubular member 11 projects forwardly from the cross member 12 and is provided with opposed openings 13 in which the balls 10 are movable into and out of locking position. The outer ends of the openings 13 are sufficiently restricted in diameter to prevent the balls from dropping out of the openings. A slide rod 14 movable in the bore of the tubular member 11 has an annular groove 15 which upon being brought into registry with the balls in the openings 13 will permit the balls to move into unlocking position in the groove 15. When the groove 15 is out of registry with openings 13, the balls 10 are held in extended or locking position by contact with rod 14. Movement of the rod 14 is limited to unlock and locking positions by means of pins 14a fixed to the member 11 and extending into slots 14b in the rod.

The slide rod 14 is movable into unlocking position by means of the lanyards 3 which is secured to an eye 16 on the outer end of a reduced portion 17 of the rod 14. The reduced portion 17 is slidable through a pair of connected tubular members 18 and 19 extended from the rear side of the cross member 12. A coiled spring 21 confined in the tubular member 19 between a shoulder 22 thereon and a shoulder 23 on the rod 14 urges the rod forwardly to occupy a locking position in which the balls 10 are engaged by the rod 14 so as to protrude from the openings 13 in the tubular member 11.

Latch means are provided to releasably hold the slide rod 14 in unlocking position, to prevent the spring 21 from urging the rod 14 back into locking position when the lanyard 3 or lanyard 4 is released after being operated to move the rod into unlocking position. This latch means is also constructed to release slide rod 14 for movement by the spring 21 into locking position when the tubular member 11 is inserted into socket 7 of the female coupling member 1 sufficiently to dispose the balls 10 in the socket adjacent the depressions 9 whereby when the balls register with these depressions they will be forced by the rod 14 into the depressions as the spring 21 urges the rod into locking position.

As here provided, the latch means includes a sleeve 25 slidable on the tubular member 11 with one end guided in a flanged cap 26 surrounding the tubular member and abutting the cross member 12. A coiled spring 27 confined between the cap 26 and the inner end of the sleeve 25 biases the sleeve outwardly from the cap 26. The sleeve 25 is provided internally with an inner counterbore forming an inner annular shoulder 28 and is provided with a larger outer counterbore in the outer end portion thereof for forming an outer annular shoulder 29. These shoulders limit the spring effected movement of the sleeve 25 by coming into contact with a latch pin 30 slidable radially in an opening 31 in the tubular member 11, the pin having rounded ends to engage the inner surface of the sleeve 25 and the rod 14 respectively. In the rod 14 is an annular groove 32 which is slightly forward of the pin 30, as shown in FIG. 3, when the coupling members are locked together, the outer shoulder 29 on the sleeve 25 being then in contact or substantially in contact with the pin 30.

When the male coupling member 2 is uncoupled from the female coupling member 1 as shown in FIG. 3a as the result of lanyard effected movement of the slide rod 14, the pin 30 is forced into the groove 32 on the rod so as to clear the outer shoulder 29 whereupon the spring 27 will

urge the sleeve outwardly so that the inner shoulder 28 stops against the pin 30 (see FIG. 3a) with the latter than held in the groove 32 by the small inner counterbore, thereby locking the slide rod 14 in unlocking position

5 urge the sleeve outwardly so that the inner shoulder 28 stops against the pin 30 (see FIG. 3a) with the latter than held in the groove 32 by the small inner counterbore, thereby locking the slide rod 14 in unlocking position

10 When the tubular member 11 of the male coupling member 2 is inserted into the socket 7 in the female coupling member 1, sufficiently to dispose the retracted balls 10 in the socket 7, the outer end of the sleeve 25 encounters the bevelled outer ends of the member 8 in the female coupling member 1 and this causes the sleeve to be moved rearwardly to bring shoulder 29 rearwardly of the pin 30. When this takes place the rod 14 is urged outwardly by the spring 21 and this causes the pin 30 to cam out of the groove 32, thereby releasing the rod 14 so that as the rod continues to move outwardly, the balls 10 will also cam out of the groove 15, and protrude from openings 13 into the depressions 9 to lock the coupling members together.

15 The female coupling member 1 is also provided with releasing means operable to move the rod 14 into unlocking position in response to a pull on the lanyard 4, this releasing means being operable to engage the outer end of the rod exposed at the outer end of the tubular member 11, so as to push the rod into the unlocking position hereinbefore described.

20 As shown in FIG. 3, the lock releasing means in the female coupling member operable in response to a pull on the lanyard 4, includes a slide plate 35 in the housing 6 and to which the lanyard 4 is secured by fastenings 36. Links 37 pivotally connect the plate 35 with a pair of levers 38 fulcrumed as at 39 in the housing 6 and having ends in contact with the outer end of the slide rod 14. The slide plate 35 is provided with a slot 40 through which a fastening element 41 extends, to limit sliding movement of the plate, this fastening element being also employed to hold within the housing a plate 42 to which the one end of the belt A is secured in any suitable manner. A spring 43 fixed at ends to the plate 35 bears against the fastening element 41 so as to hold the releasing means normally in a position in which it is ready to be operated. When the lanyard 4 is pulled, the slide plate 35 is retracted and through the links 37 causes the levers 38 to move the rod 14 into the same unlocking position that it occupies in response to a pull on the lanyard 3, the rod 14 being then latched in unlocking position in the same manner as described in connection with operation of the lanyard 3 to unlock the coupling members 1 and 2.

25 It should be noted that the two coupling members 1 and 2 are capable of a hinge action about the axes of the locking balls 10, as indicated by the dashed lines in FIG. 2, whereby the coupling members will comfortably conform to the curvature of the body of the user.

30 A modified form of this invention as shown in FIGS. 6, 7 and 7a, includes a belt A1, which corresponds to the belt A shown in FIGS. 1-5, and is provided at its ends with a female coupling member 45 and a male coupling member 46.

35 The female coupling member 45 includes a housing 47 which forms a socket for reception of the male coupling member 46. Within the housing 47 is a locking plate 49 having one end pivoted as at 50 to the housing with its other end disposed to be urged by a leaf spring 51 into locking position. The spring 51, as shown in FIG. 7, is fixed as at 52 to the housing 47 and bears on the plate 49 so that the latter is biased into position locking the male coupling member to the female coupling member but may be moved against the action of the spring out of that position, all in a manner to be hereinafter described.

40 The male coupling member 46 includes an elongate body plate 53 to which the other end of the belt A1 is secured by fastenings 54 and which has its outer end bent back on itself to provide a locking hook or shoulder 55. This shoulder 55 will become locked in engagement with

the outer end 49a of the spring-loaded locking plate 49, as best shown in FIG. 7, when the outer end of the plate 53 of the male coupling member 46 is inserted into the housing 47 of the female coupling member 45, and moves past the outer end 49a of the plate 49, the spring 51 then causing the plate 49 to snap into engagement with the shoulder 55.

The male coupling member 46 is also provided with an elongate releasing plate 46 slidably supported on the body plate 53 by means of fastenings 57 extending through slots 58 in the plate 46. The slide plate 56 is wider than the body plate 53 and has side flanges 59 which extend along the side edges of the outer end portions thereof. The flanges 59 are provided, as shown in FIG. 7a, with bevelled cam edges 60. When the slide plate 56 is in the extended position shown in FIG. 7, with the outer end 49a of the locking plate 49 locking against the shoulder 55 of the body plate 53, the bevelled cam edges 60 on the flanges 59 of plate 56 are disposed close to and forwardly of the locking end 49a in position to engage and move the end 49a out of engagement with the shoulder 55 when the slide plate 56 is retracted in the manner to be hereinafter described.

A lanyard 3a corresponding to the lanyard 3 and which may be arranged on the belt A1 in the same manner as the lanyard 3, is secured to the slide plate 56 in any suitable manner, for example, by means of a strap 62 and fastenings 63. With this arrangement it will be apparent that a pull on the lanyard 3a will retract the slide plate 56 so that the cam edges 60 of the flanges 59 thereon will contact the locking end of plate 49a and move the plate 49 so as to disengage the locking end 49a from the locking shoulder 55 on the body plate 53, thereby unlocking the coupling members.

Means for unlocking the coupling members 45 and 46 are also provided on the female coupling member 45 and are operable in response to a pull on a lanyard 4a arranged on belt A1 in the same manner as lanyard 4 in FIGS. 1-5. Accordingly, the lanyard 4a is mounted for limited sliding movement in a strap 65 fixed to the housing 47, there being a pin 66 fixed to the housing and slidably in a slot 67 in a ferrule 68 fixed on the end of the lanyard 4a and slidably disposed under the strap 65. A pin 69 connects one end of the ferrule 68 with one end of a lever 70 pivoted between its ends as at 71 in the housing 47, it being noted that one side wall 73 of the housing is formed with a wide slot 74 and that the pin extends through this slot. As shown in FIGS. 6 and 7, lever 70 bears against the outer end of the slide plate 56 when the coupling members are locked together.

When the lanyard 4a is pulled, the lever 70 is rocked on its pivot 71 so as to shift the slide plate 56 in the direction in which the cam edges 60 of the flanges 59 on the plate 56 will contact and move the locking plate 49 out of locking engagement with the shoulder 55 on the body plate 53.

The ferrule 68 has a slot 68a through which the pin 66 extends. A coiled spring 68b confined in the slot 68a between the pin 66 and one end of this slot operates to urge the ferrule 68 forwardly and return the lever 70 to normal position ready for the next operation upon release of the lanyard 4a after the latter has been pulled to open the belt.

It will now be apparent that the modified form of this invention, as shown in FIGS. 6 and 7, may be operated to open the belt A1 responsive to either lanyard 3a or 4a being pulled.

As shown in FIGS. 8, 9 and 10, a third modified form of this invention includes a belt A3, corresponding to the belt A in FIGS. 1-5, and to the ends of which are secured a female coupling member 80 and a male coupling member 81.

The female coupling member 80 includes a housing 82 providing a socket 83 into which the male coupling member 81 is insertible so that a pivoted and spring-

loaded locking dog 84 carried by the male coupling member will be engaged in a recess 85 in the wall 86 of the housing to lock the coupling members together.

The male coupling member 81 includes an elongate body plate 87 having flanges 88 along opposite longitudinal edges and which are disposed to slidably engage opposed walls 89 of the housing 82 of the female coupling member 80 when the male coupling member is inserted into the female coupling member. A spring member 90 is mounted on the walls 89 of the body plate 87 and engages the dog 84 so as to urge the dog into locking position when the male member is inserted into the female member. It should be noted that the male and female members, as shown in FIG. 9, are formed to conform comfortably to the curvature of the body of the user.

The pivot pin 91 is of such smaller diameter than the opening in the dog 84 through which it extends that the load on the belt will be transmitted to parts of the coupling other than the pin 91. Accordingly, a flange 87' on the plate 87 abuts and embraces the pivoted end of the dog 84, to take the thrust instead of the pivot pin, the pin merely serving to hold the dog in place. This arrangement makes it possible to release or uncouple the coupling members with consummate ease, a pull on the lanyard of but a few pounds being all that is required.

The locking dog 84 is held in locking position as shown in FIG. 9, by means of a slideable latch plate 92 carried by the body plate 87 of the male member 81, this latch plate being slidably secured to the body plate 87 by means of a fastening 93 extending through a slot 94 in the latch plate and fixed to the body plate. Springs 95 fixed to the plate 87 and the latch plate 92, respectively, urge the latter into latching position to hold the dog 84 in locking position as shown in FIG. 9. When in latching position the latch plate 92 has a projection 92' thereon (see FIG. 9) which engages the free end of the dog 84 to hold it in locking position. Retraction of the latch plate 92 will remove the projection 92' from engagement with the dog 84 so that the latter will cam out the recess 85 by reason of the coengaging cam faces of the dog and recess, in pulling the coupling members apart. Retraction of the latch plate 92 may be effected by a pull on the lanyard 3b arranged in the same manner as lanyard 3 shown in FIGS. 1-5, the lanyard 3b being looped around a projection 99 on the latch plate so that the latter will slide out of latching position when the lanyard 3b is pulled.

In order to hold the dog 84 against moving back into locking position upon uncoupling the coupling members, a second latch plate 100 is slidably mounted on the body plate and is provided with a slot 101, through which the fastening 93 extends to hold the plate 100 slidably between the body plate 87 and the main latch plate 92, as seen in FIG. 9.

A spring 103 is bent around one of the fastenings 104 on the body plate 87 with its ends fastened to the body plate 87 and to the latch plate 100 to urge the latter into position for releasably holding the locking dog in retracted or unlocking position.

When the locking dog 84 is moved out of the recess 85 in uncoupling the two coupling members following a pull on the lanyard 3b, and a shoulder 84a in the dog then cams past the adjacent edge of the latch plate 100, the spring 103 will move the latch plate over the shoulder 84a, thereby releasably holding the latch dog in unlocking position.

Upon inserting the male member 81 into the female member 80, a flange 106 on the outer end of the latch plate 100 will engage the edge portion 107 of the housing 82 of the female coupling member 80 so that the latch plate will be retracted from the locking dog shoulder 84a whereby the spring 99 will urge the locking dog 84 into locked position in the recess 85.

The female coupling member 80 is also provided with means for retracting the latch plate 92 so that the locking dog 84 will move out of locking position when pressure is applied to the coupling members for opening the belt, there being a lanyard 4b arranged on the belt in the same manner as the lanyard 4 in FIGS. 1-5 and which may be pulled to retract the latch plate 92. In pulling on the lanyard 4b a pair of levers 108, pivoted as at 109 in the housing 82 of the female coupling member 80 and to which the lanyard is connected by the flexible elements 110, will be rocked alike so that the ends 111 of the levers will engage and move out of latching position the latch plate 92.

Spring means 112 on the female member 80 normally hold the levers 108 in the position shown in FIG. 8, ready to be rocked for moving the plate 92 out of latching position.

It will now be apparent that the belt and coupling unit shown in FIGS. 8, 9, and 10 readily may be unlocked and opened by pulling on either of the two lanyards 3b and 4b.

Another modified form of the invention as shown in FIGS. 11 and 12, consists of a belt A4 and lanyards 3c and 4c arranged in substantially the same manner as in FIGS. 1-5, in connection with a female coupling member 116 and a male coupling member 117.

The male coupling member 117 comprises a body 118 having a reduced end 119 adapted to be inserted into the socket-like housing 116' of the female coupling member 116.

As a means for releasably locking the coupling members together, the male coupling member body 118 is provided with a pair of locking pins 120 slidably supported in sockets 121 with their outer ends adapted to engage in recesses 122 in the housing of the female coupling member. These locking pins are limited in their outward sliding movement by means of pins 123 thereon and slots 124 in the sockets 121.

A slidable plate-like actuating member 126 is carried by the male coupling member 117 so as to extend between and in contact with the inner ends of the locking pins 120. A fastening 127 extends through a slot 128 in the slidable member 126 to slidably mount this member on the male member 117. A spring 129 urges the member 126 into locking position shown in FIG. 11. Retraction of the slide member 126 is effected by a pull on lanyard 3c which is connected as at 126' with the slide member 126. When the slide member 126 is retracted notches 130 in opposite edges thereof are moved into registry with the locking pins 120 so that the inner ends of the pins 120 may enter the notches as the pins move out of locking position in the recesses 122 of the female member 116. The outer ends of the pins 120, as here shown, are flattened and have bevelled sides 120' so as to securely lock the coupling members together. However, these bevelled ends will cam out of the recesses 122 when pulling on the coupling members to separate them after the slide member 126 has been retracted to release the locking pins.

A spring-loaded latch dog 132 is pivoted as at 133 on the male coupling member 117 and is provided with a notch 134 adapted to receive a projection 135 on the slide member 126 to latch the latter in the retracted position in which the locking pins 120 are retracted from locking positions. Upon retraction of the member 126 from locking position the projection 135 thereon will cam over the bevelled portion 132' on the dog 132 and move the latter so that the projection 135 will snap into the notch 134. Movement of the latch dog 132 to release the slide member 126 is effected in the operation of inserting the male coupling member 117 into the female coupling member when the end 132" of the dog contacts a shoulder 136 on the housing 116' of the female coupling member 116. This contact of the dog 132 with the shoulder 136 rocks the dog so that the notch 134 is retracted from the projection 135 on the slide member 126, thereby releasing the

member 126 which is biased forwardly by the spring 129 to urge the pins into locking position.

The female coupling member 116 is provided with means for retracting the slide member 126 to cause the locking pins 120 to move out of locking position incident to pulling on the lanyard 4c. This releasing means includes a pair of levers 138 pivoted as at 139 on the female coupling member 116 with their outer ends coupled by flexible elements 149 to the lanyard 4c and their inner ends abutting the adjacent end of the slide member 126. A leaf spring 141 is engaged with the pivots 139 and ends of the levers 138 in such a manner as to hold the levers in readiness for being rocked to move the slide member 126 for releasing the locking pins 120 in response to a pull on the lanyard 4c.

One of the advantages of this form of safety belt is that the two coupling members are permitted to swing with a hinge action as indicated by the dot-dash lines in FIG. 12, about the axes of the locking pins 120 to assume a V-shape which will conform somewhat to the curvature of the body of the user of the belt to add to the comfort of the user.

It should be noted that the coupling members in all forms of this invention as here shown readily lend themselves to having corners and other portions thereof which may tend to mar, damage, or injure objects, clothing, and portions of the body of the user which come into contact therewith, provided with protective coatings or coverings to prevent such marring, damage or injury.

It should be noted that each of the forms of this invention is constructed and arranged so that the release or uncoupling of the coupling elements readily may be effected by pulling on either of the lanyards, no particularly hard or heavy pull being required.

While specific structural details have been shown and described, it should be understood that changes and alterations may be resorted to without departing from the spirit of the invention as defined in the appended claims.

I claim:

1. A safety buckle comprising: a pair of separable coupling members adapted to be coupled to a belt; a projection on one of said coupling members; means on the other coupling member providing a socket to receive said projection and defining a pair of depressions in walls of the socket; a pair of locking members carried by said projection for movement into said depressions to releasably lock said coupling members together; an actuating member shiftably carried by said projection for movement into a position for moving said locking members into said depressions on and a position for releasing said locking members from said depressions; spring means biasing said actuating member into position for moving said locking members into said depressions; a lanyard connected with said actuating member operable for moving said actuating member into position to release said locking members; and means carried by said other coupling member operable for engaging and moving said actuating member into position to release said locking member.

2. The safety buckle as set forth in claim 1, including latch means operable in response to movement of said actuating member in releasing position for releasably holding said actuating member against movement into said position to lock said locking members; and latch releasing means operable upon re-engaging said coupling members with one another for releasing said actuating member.

3. A safety buckle comprising: a pair of separable coupling members each adapted to be connected to a belt; a locking plate movably carried by one of said coupling members; a projection on the other coupling member engageable by said locking plate to releasably lock said coupling members together; spring means biasing said locking plate to engage said projection; a releasing member movably carried by said other coupling members for engaging and moving said locking plate so as to release said pro-

jection; a lanyard connected to said releasing member and operable to move said releasing member for releasing said locking plate; releasing means movable on said one coupling member to engage and move said releasing member for releasing said locking plate; and a lanyard connected with said last named releasing means.

4. A safety buckle comprising: a pair of separable coupling members each adapted for connection to a belt; locking means carried by said coupling members including a dog pivoted on one of said coupling members and a locking element on the other of said members cooperable to releasably lock said coupling members together; means biasing said dog into locking engagement with said locking element; a first latch carried by said one coupling element; means biasing said latch to releasably engage and releasably hold said dog in locking position incident to movement of said dog into said locking position; means connected with said latch operable to move the latch for releasing said dog from said locking position; said dog and said locking element having cam surfaces cooperable to move said dog into unlocking position incident to separation of said coupling members; a second latch movable on said one coupling member; means biasing said second latch to engage and releasably hold said dog in said unlocking position; and means on said second latch engageable with said other coupling member upon moving said coupling members together for moving said second latch to release said dog from said unlocking position.

5. A safety buckle comprising: a pair of separable coupling members each adapted to be connected with a belt; one of said coupling members having opposed walls forming a socket therebetween; one of said walls having a depression therein; a body member on the other coupling member extensible into said socket; a locking dog pivoted on said body member for movement into and from said depression to releasably lock said coupling members together; spring means biasing said dog into locking position; a latch carried on said body member for movement to releasably hold said dog in locking position; spring means biasing said latch to engage and releasably latch said dog in said locking position; said dog and said depression having cam surfaces cooperable to move said dog into unlocking position upon separation of said coupling members; a lanyard connected to said latch operable to move said latch for releasing said dog; a second latch movably carried by said body member operable for releasably holding said dog in said unlocking position; spring means biasing said second latch to releasably hold said dog in said unlocking position; releasing means carried by said one coupling member operable to engage and move said first named latch to release said dog from locking position; a lanyard connected with said last named releasing means for operation thereof; and means embodied to said one coupling member and said second latch cooperable to move said second latch to release said dog from said unlocking position incident to moving said body member into said socket.

6. The safety buckle as set forth in claim 4 wherein means are provided on said one coupling member engageable with said dog for relieving from the pivot of said dog loads imposed on said dog while said coupling members are locked together.

7. A safety buckle comprising: a pair of separable coupling members each adapted to be connected with a belt; one of said coupling members having walls defining therebetween a socket; opposed portions of said walls having locking depressions therein; a body member on the other of said coupling members adapted to be removably mounted in said socket; a pair of locking pins slidably carried by said body member for movement into and from said depressions; an actuating member mounted on said body member between and in engagement with opposite ends of said pins for sliding movement between a first position for moving said pins into said depressions

and a second position permitting removal of said pins from said depressions; spring means biasing said actuating member into said first position; lanyard means operatively connected with said actuating member operable to move said actuating member into said second position; latch means on said body member operable to releasably hold said actuating member in said second position incident to movement of said actuating member into said second position; and means on said latch means engageable with said other coupling member upon insertion of said body member into said socket for releasing said latch means.

8. A safety belt for the occupant of a vehicle seat comprising: a belt; means anchoring the belt to the vehicle with portions of the belt disposed to be locked together around the body of an occupant of the seat; coupling members carried by said portions of the belt; locking means carried by said coupling members cooperable for for releasably locking said coupling members together upon moving said coupling members into engagement with one another; and releasing means connected to said locking means operable for unlocking said locking means and including lanyards extending in opposite directions from said coupling members, with each lanyard subject to being grasped and pulled to operate said releasing means.

9. The invention as set forth in claim 8, wherein said coupling members are preformed to conform to the curvature of the body of the user.

10. The invention as set forth in claim 8, wherein said lanyards extend around the exterior of said portions of the belt and are connected therewith for movement relative thereto at points longitudinally spaced along the belt, with portions of said lanyards forming loops subject to being grasped and pulled to effect said operation of said releasing means.

11. The invention as set forth in claim 8, wherein the ends of said lanyards that are farthest removed from said coupling members are fixed to portions of said belt that extend toward the back of said occupant.

12. A safety buckle comprising: a pair of coupling members adapted to be connected with the separable portions of an anchored safety seat belt; locking means embodied in said coupling members cooperable upon engaging said coupling members with one another to releasably lock said coupling members together; releasing means embodied in each of said coupling members operable for unlocking said locking means; and a pair of lanyards connected with said releasing means; said lanyards being disposed so that either lanyard may be grasped and pulled to effect operation of the releasing means connected therewith and thereby unlock said locking means.

13. A safety seat belt comprising: a pair of separable belt portions; means anchoring said belt portions; a pair of coupling members connected with said belt portions; locking means embodied in said coupling members cooperable when engaged to releasably lock said coupling members together with said belt portions encircling a portion of the body of an occupant of the seat; releasing means in each of said coupling members operable for unlocking said locking means; a pair of lanyards connected with said releasing means in said coupling members operable when either lanyard is pulled to actuate said releasing means to unlock said locking means; and means connecting said lanyards to said belt portions for movement relative to said belt portions and so that each lanyard is disposed in a position to be grasped and pulled at different points along its length.

14. A buckle for a safety seat belt comprising: a male coupling member; a female coupling member for reception of said male coupling member; locking means in said coupling members including a locking member movable on one of said coupling members and a locking ele-

ment on the other of said coupling members; means embodied in one of said coupling members operable to move said locking member into locking engagement with said locking element to releasably lock said coupling members together upon movement of said male coupling member into said female coupling member; releasing means in each of said coupling members arranged so that either releasing means may be operated to unlock said locking means; and a pair of lanyards each of which is connected with one of said releasing means and is operable to actuate the releasing means to which it is connected so as to unlock said locking means; said lanyards being extended in opposite directions from said buckle and connected with the belt for movement relative thereto so that either lanyard may be grasped and pulled to unlock said locking means.
